By Robert S. Carr, M.M.

UNITED STATES PATENT OFFICE.

PAUL L. BROCKARDT, OF HAMILTON, OHIO, ASSIGNOR, BY MESNE ASSIGNMENTS, TO THE OHIO LAUNDRY MACHINERY CO., OF CINCINNATI, OHIO, A CORPORATION OF OHIO.

MANGLE.

No. 897,859.

Specification of Letters Patent.

Patented Sept. 1, 1908.

Application filed November 12, 1906. Serial No. 342,946.

To all whom it may concern:

Be it known that I, PAUL L. BROCKARDT, a citizen of the United States, residing at Hamilton, Ohio, have invented a new and useful 5 Improvement in Mangles, of which the following is a specification.

My invention relates to mangles of the class wherein the linen is carried between an endless apron and a cylindrical drier under a 10 series of pressure rolls, and the objects of my improvement are to provide means for utilizing a greater or less number of pressure rolls; to move and maintain any or all of the rolls toward or from the drier; to adjust the 15 pressure of the rolls independently of their shifting mechanism, and to provide simple and durable construction together with facility of adjustment and efficiency of action. These objects are attained in the following 20 described manner as illustrated in the accompanying drawings, in which:—

Figure 1 is a transverse vertical section on the line *a—a* of Fig. 3 of a mangle embodying my improvements; Fig. 2 an end supporting 25 frame with the roll shifting mechanism in operative position; Fig. 3, a longitudinal section on the line *b—b* of Fig. 2 of one end portion of the mangle, Figs. 4 and 5, respective 30 front and side elevations with parts in section of an adjustable bearing for the pressure rolls. Fig. 6 an elevation of one of the brackets, and Fig. 7 an elevation of a housing adapted to slide therein.

In the drawings, 1 represents the end supporting frames, 2 a hollow cylindrical drier formed with hollow journals 3 whereby it is journaled therein. A driven gear 4 is secured on one of the journals for rotating the drier in the direction of the arrow. An end 35 less apron 5 partially encircles the drier in contact with its face and travels in the direction of the arrows.

6 and 7 represent the respective front and rear and 8, 9, 10, and 11, the intermediate 40 padded apron pressure rolls some or all of which may be provided with respective pinions 20 in mesh with gear 4. Said pressure rolls are capable of being moved equal distances toward or from the axis of the cylindrical drier in a radial direction.

12, 13, 14, and 15 represent the apron rolls, 45 16 the stretcher roll, and 19 the ductor bar, all constructed and arranged in the ordinary manner.

A series of brackets 28 are adjustably bolted to each of the supporting frames and provided with grooves 27 and with slots 29 and 30. Housings 23 mounted to slide within the respective brackets and in lines radiating from the axis of the drier are each provided with a slot 22 in registration with the corresponding slots 29, with a radial bar 38 movable through slot 30 and with a compression spring 24 which is adjustable by means of a hand screw 25. Bearings 21 wherein the pressure rolls are journaled are supported within the housings and maintained in contact with the bottom of slots 22 therein and under a yielding pressure by means of springs 24.

Similar disks 31 mounted to turn on the respective journal hubs of the drier are each provided with a series of cam slots 32 each of which extends in opposite directions from its cam or inclined portion in arcs concentric 55 with and at different distances from the axis of the journals. A shaft 33 journaled between the end supporting frames parallel with the face of the drier is provided with arms 34 which are connected with disks 31 by means of connecting rods 35. A detent lever 36 secured to said shaft serves to simultaneously adjust the disks in a rotative direction on the journals. The radial bars 38 are each provided with an anti-friction roller 37 60 whereby it is movably engaged with a corresponding cam slot in one of the disks. The slots may be circumferentially arranged in the disks for moving all the radial arms and housings with the pressure rolls either in an 65 outward or an inward direction simultaneously or they may be so arranged circumferentially in their relation to the radial bars as to move them successively or in pairs or in any desired order.

As shown in Fig. 2 the circumferential position of the slots in relation to the position of the respective radial bars is such that in the upward movement of the detent lever the slots will move and maintain the radial 70 bars, together with the pressure rollers 8, 9, 10, and 11, in an outward direction successively and thereafter the front and back pressure rollers 6 and 7 simultaneously and by the downward movement of the detent 75 lever said rolls will be moved toward the face of the drier in an inverse order.

In operation, it is desirable to subject some

goods to more pressure than others in their passage between the apron and the drier. By means of the detent lever one or more of the pressure rolls may be instantly moved 5 out of action or returned as the necessity of the goods may require for the most efficient result. When not in use the lever serves to relieve the apron from the pressure of all the rolls to prevent it from being injured by contact under pressure with the drier. The outward movement of the housings lifts the pressure rolls in a direction from the face of the drier by the contact of the bottom of slots 22 with the bearings therein. The inward movement of the housings carries the pressure rolls in a direction toward the face of the drier and the bottom of the slots 22 beyond the bearings, whereby the exertion of springs 24 on the bearings serves to maintain 10 the pressure rolls with the apron against the face of the drier under a yielding pressure.

Having fully described my improvement, what I claim as my invention and desire to secure by Letters Patent of the United 25 States is:—

1. In a mangle, the combination of a disk provided with a circumferential cam slot, having its end portions extended in opposite directions concentric with and at different 30 distances from the center of the disk, a bar movably engaging with the slot, and means for rotatively adjusting the disk for moving and maintaining the bar in different radial positions of adjustment.

2. The combination of a cylindrical drier, a series of pressure rolls, an apron partially encircling the drier thereunder, a series of 35 housings, bearing boxes slidably mounted therein for said rolls, springs arranged in said housings for yieldingly maintaining said boxes in a predetermined position, and cam mechanism for consecutively moving and

maintaining said housings with the rolls equal distances from the drier.

3. The combination of a cylindrical drier, 45 pressure rolls therefor, an apron movable between them and the drier, radially movable arms provided with bearing boxes wherein the rolls are journaled, and hand actuated cam mechanism for successively 50 moving and maintaining a plural number of arms with the rolls equal distances from the axis of the drier.

4. The combination of a rotative drier, 55 pressure rolls therefor, an apron movable between them and the drier, radially movable bars wherein the rolls are journaled, similar disks mounted at opposite ends of and concentric with the axis of the drier, said disks being each provided with a series of 60 circumferential cam slots, anti-friction rollers secured on the bars and movably engaging with the slots, and hand actuated mechanism for rotatively adjusting the disks, whereby the bars and rolls may be moved in 65 predetermined non-simultaneous order and maintained in different positions of adjustment.

5. In a mangle, a rotatively adjustable disk provided with a series of cam slots 70 which are extended at their respective ends in arcs concentric with and at different distances from the axis of the disk, radially movable bars engaging with the slots and means for rotatively adjusting the disk, 75 whereby the bars may be moved in predetermined order and maintained in predetermined positions in relation to the axis of the disk.

P. L. BROCKARDT.
